(57) **CLAIM**

The ornamental design for a front portion of a motor vehicle, toy replica and/or other replicas, as shown and described.

DESCRIPTION

FIG. 1 is a front perspective view of a front portion of a motor vehicle, toy replica and/or other replicas.

FIG. 2 is a left side view thereof;

FIG. 3 is a right side view thereof;

FIG. 4 is a front view thereof;

FIG. 5 is a rear view thereof; and,

FIG. 6 is a top view thereof.

The vehicle portions shown in broken lines form no part of the claimed design.
